UNITED STATES PATENT OFFICE.

STANISLAW SZOSTAK, OF CRANBERRY, WEST VIRGINIA.

DESIGN FOR A WEAPON.

48,208.

Specification for Design.

Patented Nov. 23, 1915.

Application filed August 17, 1915. Serial No. 46,005. Term of patent 7 years.

To all whom it may concern:

Be it known that I, STANISLAW SZOSTAK, a subject of the Emperor of Austria-Hungary, residing at Cranberry, in the county of Raleigh and State of West Virginia, have invented a new, original, and ornamental Design for a Weapon, of which the following is a specification, reference being had to the accompanying drawing, forming part thereof.

The figure is a perspective view of a weapon, showing my new design.

I claim:

The ornamental design for a weapon, as shown.

STANISLAW SZOSTAK.

Witnesses:

PETER NATONEK,
FRANK KRIBIK.
